(57) **CLAIM**

The ornamental design for a medication dispensing device for loading tablets and capsules into small bags, as shown and described.

DESCRIPTION

FIG. 1 is a perspective view of a medication dispensing unit for loading tablets and capsules into small bags, showing my new design;

FIG. 2 is a top plan view thereof;

FIG. 3 is a front elevational view thereof;

FIG. 4 is a rear elevational view thereof;

FIG. 5 is a bottom plan view thereof;

FIG. 6 is a left side elevational view thereof; and,

FIG. 7 is a right side elevational view thereof.

The broken line(s) which define the bounds of the claimed design form no part thereof.
